UNITED STATES PATENT OFFICE

2,422,976

NOISE REDUCER FOR AMPLITUDE MODULATION RECEPTION

Madison G. Nicholson, Jr., Snyder, N. Y., assignor to Colonial Radio Corporation, Buffalo, N. Y.

Application June 29, 1944, Serial No. 542,739

7 Claims. (Cl. 250—20)

1

This invention relates to noise limiting circuits, and more particularly to noise limiting circuits adapted and arranged for use in the reception of amplitude modulated signals.

Various arrangements have been suggested in the past for limiting the response of receivers for amplitude modulated signals to noise of the impulse type, such as that produced in the loud speaker by automobile ignition, vacuum cleaner motors, electric shavers, and the like; and these generally, to the extent that they are operative, are based on the application of the principle of limiting, employing a tube or tubes which saturate at values corresponding to one hundred per cent modulation of the strongest signal to be received or in some cases one hundred per cent modulation of the signal actually being received. In the latter case the circuits limit the noise occurring in the output circuit to that equivalent to one hundred percent modulation.

In accordance with my invention, I am able to still further reduce the noise which remains even when such systems are operating properly, and which would otherwise pass through the limiting devices.

Among the objects of my invention may be mentioned the following:

To provide a circuit which will eliminate or largely reduce noise would otherwise be stronger than the signal.

To provide a system in which the noise impulse previously limited to one hundred per cent level are prevented from distorting the wave form of the audio currents except to a very minor degree.

To provide a circuit which will maintain to a substantial degree the desired wave form of the audio signal in the presence of noise which would otherwise greatly distort it, even though limited to the level of one hundred per cent modulation.

To provide a radio receiver which is relatively immune to noise of the electrical impulse type and which will operate with relative freedom from noise in the immediate neighborhood of other electrical apparatus, such as automobile ignition systems, electric shavers, vacuum cleaners, and the like.

Still other objects and advantages of my invention will be apparent from the specification.

The features of novelty which I believe to be characteristic of my invention are set forth with particularity in the appended claims. My invention itself, however, both as to its fundamental principles and as to its particular embodiments,

2

will best be understood by reference to the specification and accompanying drawing, in which

Fig. 1 is a circuit diagram of apparatus in accordance with my invention, and

Fig. 2 is a series of curves illustrating the operation of the circuit in accordance with my invention.

Referring now more particularly to the drawing, my invention is preferably applied just before the final detection of the received signal. Thus 10 may represent the final coupling transformer from the last intermediate stage of a superheterodyne receiver or the last T. R. F. stage of a T. R. F. receiver.

15 The transformer 10 may comprise primary coil 10a shunted by tuning condenser 10c and secondary coil 10b shunted by condenser 10d. Since the parts of the receiver prior to this point are well understood in the art and per se are not part

20 of this invention, they are not shown or described. The signal supplied to the coil 10b may be passed through condenser 11 and impressed upon the rectifier diode 12, which may comprise cathode 12c and anode 12a. The currents rectified by the diode 12 pass through resistances 13 and 14 connected in series and having their upper end connected to the diode anode 12a and their lower end to ground, as indicated.

25 Resistance 14 may be shunted by by-pass condenser 15, which eliminates from resistor 14 any radio frequency currents. From the common point of resistances 13 and 14 a connection may be made to anode 20a of rectifier diode 20, having also cathode 20c. The latter may be connected to ground through condenser 24, and may supply audio signals to the audio frequency amplifier through condenser 21, resistance 22, and volume control resistance 23, all being connected in series between cathode 20c and ground. The audio

30 frequency signals may be taken from a variable point on resistance 23 and impressed on the input circuit of any suitable audio frequency amplifier if desired.

35 Connected from the high potential side of tuning condenser 10d I may provide condensers 16 and 17 in series to ground, and from the common point of these two condensers a connection may be made to the cathode 26c of diode 26 and also to ground through resistance 25. From the anode 12a of diode 12 a connection may be made through resistance 18 to anode 26a of diode 26, which anode may be connected to ground through condenser 27.

40 An additional diode 29 may be provided having its anode 29a connected to the cathode 20c and

its cathode 29c connected through resistance 30 and condenser 28 to the common point of condensers 16 and 17, and the end of resistance 18, which is connected to anode 26a, may be connected through resistance 19 to the common point of condenser 28 and resistance 30. The operation of this circuit will now be described.

Diode 12 is the signal demodulator and, as will be understood, produces a rectified current flowing through resistances 13 and 14 in a direction such as to make the end of resistance 13, which is connected to the anode 12a, negative with respect to ground. Thus the potential of the anode 12a fluctuates with respect to ground, being at all times more or less negative, depending upon the strength of the signal, but never, under any circumstances, becoming positive.

At this point it should also be kept in mind, for aid in understanding the operation of my invention, that electrical impulses of the noise type likewise make the anode 12a negative with respect to ground to a greater or less degree, depending on the amplitude of the noise impulse, and never, under any circumstances, make it positive. This is clearly shown in Fig. 2, in which the curve E (B) represents the audio wave form and is actually the potential difference between point B and ground.

It will be seen from this that the average value of EB is negative and represents the axis of the modulation curve EB, which can never go above the zero line. For normal operation; that is, with no noise, a reduced signal voltage is applied to the anode 20a of diode 20 through the voltage divider formed by resistances 13 and 14, which are preferably chosen so that the voltage from point A to ground is about one-third that from point B to ground. So long as the anode 20a is positive with respect to cathode 20c, diode 20 will act like a wire connection and will pass the audio frequency signal through condenser 21 and resistances 22 and 23. The potential of point A with respect to ground is shown in curve EA.

In the absence of noise, anode 20a is positive with respect to cathode 20c, since the latter derives its potential from point B through resistances 18, 19, and 30, and diode 29, and point B is more negative than point A.

Suppose, now, a short, sharp noise impulse is received, as indicated by the peak N on curve EB. In the relatively short time during which such pulse occurs, the potential of point C will not have time to rise appreciably, because of the connection of point C to condenser 27. However, the potential of point B will go sharply negative as indicated in Fig. 2, and the potential of point A, as shown on the curve EA will also go sharply negative by one-third of the value of the change in potential of point B. This is sufficient to make anode 20a negative with respect to cathode 20c, and thereby stops the flow of current through diode 20.

In this way noise pulses which would appear in the audio output would limit to a finite value (usually one hundred per cent modulation level), regardless of the magnitude of the incoming pulses above the critical limiting value. Such a condition would be as indicated in curve EL, but even these limited pulses are prevented by my invention as follows.

Since the voltage across condenser 27 will not follow the normal changes in voltage at point B brought about by modulation, it is necessary to choose such a ratio of resistances 13 and 14 that

condenser 27 is kept charged to a value just sufficient to accommodate one hundred per cent modulation of the incoming signal without the current through diode 20 being reduced to zero.

While a noise pulse is being received, as already stated, diode 20 acts as an open circuit and the voltage at point D will begin to approach the voltage at point C, the rate of approach being determined primarily by the time constant of resistance 30 and condenser 24. Should this process complete itself, the resulting noise pulse in the output would have an amplitude equal to one hundred per cent modulation, as shown in curve EL. However, this process is not allowed to complete itself because the noise pulse is rectified in the diode 26, producing a voltage which makes point E more positive than point D, thus opening the circuit through diode 29.

Thus during the reception of noise pulses point D is isolated from all input sources because both diodes 20 and 29 no longer pass current, and point D simply floats during the small time interval of the noise pulse. Diode 26 is biased to cut-off for all signals equal or less than normal modulation peaks, this being determined by the ratio of condensers 16 and 17. The final or output wave then has the form shown in curve Eo, from which it will be seen that the only effect of the noise impulse is to produce a small irregularity or dimple in the final audio wave form.

For the purpose of making the disclosure complete, but not by way of limitation, the following table of values is given:

	Resistances	Values	Condensers	Values
25	68,000 ohms		16	25 mmf.
13	30,000 ohms		17	50 mmf.
14	15,000 ohms		27	0.1 mf.
18	0.47 megohms		24	0.0005 mf.
40	0.1 meghoms		21	0.01 mf.
30	0.47 megohms		28	0.01 mf.
23	2 megohms		15	40 mmf.
22	0.1 meghoms			

While I have shown and described certain preferred embodiments of my invention, it will be understood that modifications and changes may be made without departing from the spirit and scope thereof, as will be clear to those skilled in the art.

In this application I have particularly pointed out and distinctly claimed the part, improvement, or combination which I claim as my invention or discovery, and I have explained the principles thereof and the best mode in which I have contemplated applying those principles so as to distinguish my invention from other inventions.

I claim:

1. In a radio receiver of the amplitude modulation type, in combination, a signal demodulator, a capacity charged thereby, an audio output circuit containing capacity, a connection between said output circuit and said demodulator and a second connection between said output circuit and the first capacity, and means for interrupting both of said connections during the occurrence of noise pulses substantially exceeding the level of one hundred per cent positive modulation peaks.

2. In a radio receiver of the amplitude modulation type, in combination, a signal demodulator, a capacity charged thereby, an audio output circuit containing capacity, a connection between said output circuit and said demodulator and a second connection between said output circuit and the first capacity, and means comprising a pair of diodes for interrupting both of said connec-

tions during the occurrence of noise pulses substantially exceeding the level of one hundred per cent positive modulation peaks.

3. In a radio receiver of the amplitude modulation type, in combination, a signal demodulator, a capacity charged thereby, an audio output circuit containing capacity, a connection between said output circuit and said demodulator and between said output circuit and the first capacity, and means comprising a pair of diodes and means for maintaining the anodes thereof negative with respect to their cathodes for interrupting both of said connections during the occurrence of noise pulses substantially exceeding the level of one hundred per cent positive modulation peaks.

4. In a radio receiver of the amplitude modulation type, in combination, a signal demodulator, a capacity charged thereby, an audio output circuit containing capacity, a connection between said output circuit and said demodulator and between said output circuit and the first capacity, and means comprising a pair of diodes and means for maintaining the anodes thereof negative with respect to their cathodes for interrupting both of said connections during the occurrence of noise pulses substantially exceeding the level of one hundred per cent positive modulation peaks, having the anode of one and the cathode of the other connected together.

5. In a radio receiver of the amplitude modulation type, in combination, a signal demodulator, a capacity charged thereby, an audio output circuit containing capacity, a connection between said output circuit and said demodulator and between said output circuit and the first capacity, and means comprising a pair of diodes and means for maintaining the anodes thereof negative with respect to their cathodes for interrupting both of said connections during the occurrence of noise pulses substantially exceeding the level of one hundred per cent positive modulation peaks, said last mentioned means comprising a third diode arranged to rectify noise pulses having an amplitude substantially exceeding the level of one hundred per cent positive modulation peaks.

6. In a radio receiver of the amplitude modu-

- lation type, in combination, a signal demodulator, a capacity charged thereby, an audio output circuit containing capacity, a connection between said output circuit and said demodulator and between said output circuit and the first capacity, and means comprising a pair of diodes and means for maintaining the anodes thereof negative with respect to their cathodes for interrupting both of said connections during the occurrence of noise pulses substantially exceeding the level of one hundred per cent positive modulation peaks, said last mentioned means comprising a third diode arranged to rectify noise pulses having an amplitude substantially exceeding the level of one hundred per cent positive modulation peaks, said last diode being biased to prevent operation in response to voltages less than the level of one hundred per cent positive modulation peaks.
7. In a radio receiver of the amplitude modulation type, in combination, a signal demodulator, an audio output circuit containing capacity, and a connection between said output circuit and said demodulator, said connection comprising a pair of diodes with the anode of one diode connected to the cathode of the other, and the audio output circuit being connected to the common point of said diodes.
